MICROMANIPULATOR

Jacques Monchablon, Marignane, France

Application August 7, 1947, Serial No. 767,167
In France November 21, 1940Section 1, Public Law 690, August 8, 1946
Patent expires November 21, 1960

6 Claims. (Cl. 88—40)

1

The present invention relates to micromanipulators (such for instance as used in histology, bacteriology, etc.) and its object is to provide an apparatus of this kind which is better adapted to meet the requirements of practice than those made up to this time, in particular from the point of view of simplicity of construction, ease of operation and accuracy.

A preferred embodiment of my invention will be hereinafter described with reference to the accompanying drawings, given merely by way of example, and in which:

The only figure is a diagrammatic perspective view of a micromanipulator made according to my invention.

The micromanipulator shown by the drawing is mounted in a casing or support 1 of suitable shape the base of which is shown in solid lines while its sides are diagrammatically shown in dotted lines; on this base of support 1 is fixed an angle piece 2 constituting a bearing for a journal 3 for the oscillation of a piece or block 4. This block is provided at its front end with a disc 5 fixed therewith, coaxial with journal 3 and fitted with an axial spindle 6 rigid therewith around which is wound the end of a string 7 connected to the end of a rod 8 of the needle holder, a return spring 9 being provided at the end of this string 7.

Perpendicularly to the axis of journal 3 there is journaled in block 4 a shaft which carries, rigid therewith, on the right hand side of block 4, a disc 10 having an axial spindle 6a fixed thereto, around which spindle is wound a string 11 passing about a return pulley 12 and secured to the end of the needle holder rod 8.

Said shaft carries, rigidly mounted on its left hand end, a rod 13 bent at right angles so as to have a vertical portion, which is connected through a coupling piece 14 with a rod 15 which constitutes the single control member of the micromanipulator. This rod 15 is engaged at its lower part in a flexible sleeve 16, such as a rubber tube, which connects rod 15 with a threaded rod 17 capable of rotating freely in base 1. On this rod 17 can move a nut 17a rigid with a rod 18 on which is fixed a string 19 connected to the end of needle holder 8 and also provided with a return spring 20 in line therewith.

The rod 8 of the needle holder is fixed in an adjustable piece 21 provided with return springs 22 and 23. On the free end of the rod 8 of the needle holder is fixed the clip 24 which holds needle 25, shown in dotted lines.

Each of the discs 5 and 10 is provided with a 53 rection or the other.

2

fixation point 6b to which are secured the ends of strings 1a and 11a connected to strings 7 and 11 and stretched by pulling member 26.

This micromanipulator works as follows:

5 First, it should be well understood that when the handle provided at the top of rod 15 is urged toward either the right hand side (arrow Ba) or the left hand side (arrow Aa), coupling piece 14, rod 13 and block 4 are caused to rotate about the 10 axis of bearing 2 with respect to support 1. Movement of rod 15 to correspond to this rotation is made possible by the deformable connection 16 existing between said rod and support 1.

In its position of rest the needle carrying rod 8 15 is in a horizontal position, same as block 4, and control rod 15 is in a vertical position. If, now, it is desired to move needle 25 towards the right (direction A) it suffices to move the handle of rod 15 towards the left (direction Aa) which will 20 have for its effect, as above explained, to rotate block 4 in a counter-clockwise direction and to cause axial spindle 6 to rotate about its axis, thus exerting on string 7 a pull which will stretch spring 9 and move toward the left the end of 25 rod 8, the point of oscillation of which is constituted by the centre of piece 21.

In order to move needle 25 towards the left (direction B) it suffices to move the handle of rod 15 towards the right (direction Ba) which 30 will have for its effect to rotate block 4 in the clockwise direction, to release string 7 and to enable spring 9 to contract, pulling the end of rod 8 toward the right. The two movements toward the right and toward the left are thus produced in the horizontal plane by one kind of displacement of rod 15. Vertical displacement of 35 needle 25 in a downward direction (direction C) will be obtained by causing rod 15 to turn about itself (direction Ca) which will cause an upward movement of nut 17a along threaded rod 17, causing rod 18 to pivot upwardly and relieving string 19, which enables return spring 20 to contract so as to move rod 8 upwardly. As this rod pivots about portion 21, it will cause the point of needle 40 25 to move downwardly. Movement of the needle in the upward direction (D) will also take place by rotating rod 15 upon itself, but in the opposite direction (direction Da) which has for its effect to move nut 17a downwardly on threaded rod 17,

45 to move rod 8 downwardly while stretching spring 20, and to move the end of needle 25 upwardly. Upward and downward vertical displacements of needle 25 are thus ensured in a vertical 50 plane by rotation of rod 15 about itself in one direction or the other.

Displacement of needle 25 in the longitudinal direction E is obtained by pulling rod 15 rearwardly, which has for its effect to rotate spindle 6a about its axis and thus to pull string 11, which, through return pulley 12, drives rod 8 forwardly and imparts this horizontal movement to piece 21, while stretching springs 22 and 23. Backward movement of needle 25 will be obtained by bringing rod 15 back to its initial position, which will relieve string 11 and enable springs 22 and 23 to move needle 25 toward its initial position.

These two longitudinal displacements are thus obtained by a third kind of displacement of rod 15.

If it is desired to increase the amplitude of the displacements above described, it suffices to stretch strings 1a and 11a by means of pulling member 26. As their points of fixation 6b on discs 5 and 10 are at a distance much greater than the radius of spindles 6 and 6a, it will be understood that the displacements of needle 25 in the horizontal plane are considerably increased.

Due to the simplicity of its construction and operation and to the precision of its working, my apparatus constitutes a very important improvement in the art. Furthermore, it is very cheap to manufacture.

What I claim is:

1. A micromanipulator for controlling the displacements of an object which comprises, in combination, a holder of elongated shape for said object, a support for said holder, a plurality of springs normally located in the same plane at right angles to the longitudinal direction of said holder interposed between said support and points of an intermediate portion of said holder for free elastic suspension of said holder, a single control member movably carried by said support, three strings secured to said holder at a point thereof at a distance from the plane of said springs, means between said control member and one of said strings for pulling said last mentioned string in one direction at right angles to said longitudinal direction in response to a given kind of displacements of said member with respect to said support, a spring between said support and the point of fixation to said holder of said last mentioned string for opposing the pulling thereof in said direction, means between said control member and another of said strings for pulling said last mentioned string in another direction at right angles to said longitudinal direction in response to another kind of displacement of said member with respect to said support, a spring between said support and the point of fixation to said holder of said last mentioned string for opposing the pulling thereof in said last mentioned direction, said springs being normally located in the same plane, at right angles to said longitudinal direction, and means between said control member and the point of fixation to said holder of the third of said strings for pulling said third string in said longitudinal direction in response to a third kind of displacement of said member with respect to said support.

2. A micromanipulator according to claim 1 including three driving pieces movably mounted with respect to said support and operatively connected to said control member to be rotated about three different respective axes in response to said displacements of three different kinds of said control member, said strings being fixed to said driving pieces respectively at points thereof distant from their respective axes of rotation, said

pieces belonging to the means for pulling said strings.

3. A micromanipulator according to claim 2 further including supplementary string elements 5 each interposed between a point of one of said first mentioned strings and a point of the corresponding driving piece located at a distance from the axis of said piece greater than the distance from the first mentioned point of fixation 10 of the corresponding first mentioned string to said driving piece, said string elements being normally loose, and means for stretching said string elements to make them effective as transmission means between said driving pieces and said holder.

4. A micromanipulator according to claim 2 in which said control member includes two rod portions, one of said rod portions being journalled about its own axis in said support, and a rubber 20 sleeve for coupling said first rod portion with the second one, the three kinds of movements of said member consisting in oscillations of the second rod portion in two different planes passing through said last mentioned axis and a rotation 25 of said second rod about its own axis.

5. A micromanipulator for controlling the displacement of an object which comprises, in combination, a support, a holder for said object, elastic suspension means deformable in three distinct 30 spatial directions interposed between said support and a central portion of said holder, three strings fixed to said holder at a distance from said central portion, a single control member movably carried by said support to have three 35 distinct kinds of displacement with respect thereto, transmission means between said control member and said strings to pull them in the respective directions of the three axes of a three dimensional system of coordinates in response to 40 said three kinds of displacement of said control member respectively, and spring means interposed between said support and said holder for yieldingly opposing the pulling actions of said strings.

45 ✓ 6. A micromanipulator for controlling the displacements of an object which comprises, in combination, a holder of elongated shape for said object, a support for said holder, a plurality of springs normally located in the same plane at

50 right angles to the longitudinal direction of said holder interposed between said support and points of an intermediate portion of said holder for free elastic suspension thereof, a single control member movably carried by said support, a 55 block pivoted to said support about an axis parallel to the longitudinal direction of said holder, a spindle rigid with said block and located along said pivot axis thereof, a string interposed between the periphery of said spindle and a point of

60 said holder located at a distance from the plane of said springs to pull said point of said holder in a direction at right angles to the longitudinal direction of said holder in response to a rotation of said spindle in one direction, spring means 65 between said point of said holder and said support for directly opposing the pull exerted by said string, a shaft journalled in said block at right angles to the pivot axis thereof, a disc rigid with said shaft, a spindle fixed to said disc, a string interposed between the periphery of said last 70 mentioned spindle and a point of said holder to pull said holder at least substantially in the longitudinal direction thereof in response to a rotation of the second mentioned spindle in one direction, means interposed between said second men-
